(57) **CLAIM**

The ornamental design for a handguard for a firearm, as shown and described.

DESCRIPTION

FIG. 1 is a perspective view of a handguard for a firearm according to the disclosure;

FIG. 2 is a front view thereof;

FIG. 3 is a rear view thereof;

FIG. 4 is a top view thereof;

FIG. 5 is a bottom view thereof;

FIG. 6 is a side view thereof; and,

FIG. 7 is a side view thereof.

The broken lines in the drawings disclose unclaimed portions of the handguard for a firearm and form no part of the claimed design.

1 Claim, 7 Drawing Sheets
